UNITED STATES PATENT OFFICE

HANS F. JORGENSEN, OF BROOKLYN, NEW YORK; NORMAN F. JORGENSEN EXECUTOR
OF SAID HANS F. JORGENSEN, DECEASED

MEANS FOR AND METHOD OF ESTABLISHING COMMUNICATION

Application filed May 25, 1926. Serial No. 111,499.

This invention relates to means for and methods of establishing communication, and more especially to such means and methods as applied to establishing communication between ships.

Heretofore difficulty has been experienced in the work of giving relief to vessels in distress during high storms at sea. In these circumstances, it is impossible to row life-boats from one ship to another on account of the high velocity of the winds which often are of hurricane proportions and also on account of the high seas which are usually running. Attempts have been made to drift life-boats from a rescuing vessel to one in distress but these attempts have always proved futile. In drifting a life-boat, it is necessary to attach a heavy line; for instance, a three-inch hawser, to the life-boat, and upon being launched this hawser sinks into the water in the shape of a very large arc, the weight of which is sufficient to prevent the life-boat ever reaching the vessel in distress. It will be seen, therefore, that some method or means of propelling a life-boat from one vessel to another would in many instances result in the rescue of otherwise doomed seamen.

An object of the present invention is to provide means for and methods of drifting a life-boat from one vessel to another.

A more comprehensive understanding of the features and merits of this invention can be obtained by reference to the accompanying drawings illustrating a preferred embodiment of the same, wherein

Figure 1 is a perspective view of the invention in practical use;

Fig. 2 is a rear view of the sail applied to the life-boat with a portion of the mast broken away; and

Fig. 3 is a side view of the mast and sail applied to the life-boat.

Referring now to the drawings, 10 indicates a vessel in distress, 11 a vessel attempting to establish communication with the disabled ship and 12 the life-boat by which such communication is established. The life-boat in this instance is of the type ordinarily carried by seagoing vessels and is provided with

certain auxiliary equipment for rendering the drifting thereof from one vessel to another possible. Such equipment comprises a sail 13 of triangular shape and of relatively small height; for example, about six feet, 55 and of proportionately narrow width. The sail 13 is constructed of the heaviest canvas procurable and the edges thereof are bound with rope 14 adding strength thereto and aiding in the fastening thereof to the life-boat. The rope 14 is provided with loops or grommets at each of the lower corners thereof and with a loop or grommet 16 at the top thereof. Thimbles are provided in each of the grommets to prevent chafing of the rope 60 thereof. The grommets 15 are utilized for securing the lower corners of the sail to the gunwales of the life-boat 12. A line 17, preferably of wire, is secured to the grommet 16 and passes through sail block or 65 sheave 18 near the top of the mast 19 and is then secured to one end of the boat by the usual block and tackle 20. The mast in this instance is a short heavy spar provided at the bottom with a step 21 which may be seated 70 in a suitable socket in the bottom of a life-boat. The mast is otherwise secured in the boat in the usual manner; that is, a portion of one of the seats 22 is cut away in the shape 75 of a semicircle into which the mast fits and a 80 semicircular hasp 23 is fastened to the edge of the seat adjacent to this cut-away portion so that it may be clamped around the mast in any suitable manner. As illustrated, the hasp is provided with a slot in the free end 85 adapted to fit over an eyebolt 24 driven into the seat and to be locked by a pin 25. A second wire 26 attached to the top of the mast is connected to the opposite end of the boat 90 from the wire 17 by similar block and tackle 95 27 for securely holding the mast in upright position.

In order that the sail may be hoisted or lowered quickly and may be held against the mast 19, it is provided with a reinforcing strip 95 30 extending centrally the length thereof in which are riveted metallic eyelets or grommets 31. A rope 32 secured at the lower edge of the sail passes through each of the eyelets in turn and around rings 33 at each eyelet. 100

The other end of the rope is fastened to the top point of the sail adjacent to the loop 16. The rings 33 are somewhat larger in diameter than the mast 19 so that they will be free 5 readily to move up and down thereon. From this, it will be seen that with the sail in a collapsible position, by merely tightening the line 17 it will be raised and held to the mast by the rings 33.

10 In the operation of the system, let it be assumed that the vessel 10 is in distress and is incapable of aiding itself in any manner. The rescuing vessel 11 after approaching as near as possible to the vessel 10, which distance in a hurricane would amount to at least a quarter of a mile, steams gradually to a point just before dead windward of the disabled ship. During the approach to this point, the life-boat 12 is equipped with the 15 mast 19 and the sail 18, and a heavy line 40 is attached to the bow of the boat. It is then launched and permitted to drift until the wind strikes the sail, at which time it will be driven steadily on, keeping the line 40 in 20 taut relation thereto. After the boat has sailed a distance approximately equal to that between the ships, the vessel 11 steams on to and beyond the point of dead windward, thereby drawing the life-boat into contact 25 with the ship 10. If so desired, a buoy 41 may be attached to the stern of the boat 12 by a relatively short line 42 of length, for example, of one hundred feet. As soon as the boat 12 is close to the ship 10, members of 30 the crew thereof may secure either the line 40 or the line 42, and thereby assume control of the boat 12. This control having been assumed, the sail is immediately lowered to prevent the boat drifting away from the ship, 35 and, if so desired, the hawser 40 may be cut. The shipwrecked seamen may then board the life-boat and, if desired, raise the sail, causing the boat to drift away from the disabled ship. The rescuing vessel 11 steaming in a 40 circle around the ship 10 then will be in position to pick up the survivors.

45 If so desired, the hawser 40 need not be cut, but the boat with its complement of shipwrecked seamen may be drawn directly to the ship 11. Should the first attempt to sail the life-boat to the ship prove futile, the vessel 11 steaming in a circle could repeat the performance upon reaching windward of the ship 10, as will be evident from the drawings.

50 It will readily be seen that the present invention provides a new and efficient method and means for drifting a life-boat from one ship to another, and it will be seen also that the absence of a large amount of tackle on the life-boat minimizes the danger of such tackle being fouled by débris from the disabled vessel which would in most instances result in the loss of the life-boat. It will be 55 seen also that either the mast alone or the

mast and sail will serve as a signal to a rescuing vessel, thereby forming a better signalling means than an oar as is the usual practice.

It is to be understood that the present invention is not to be limited by the illustrated embodiment, but only by the scope of the appended claim.

5 I claim:—

6 The combination with a sail and a line for 75 raising the same, of means for holding said sail against a mast comprising a plurality of rings slideable on said mast, a plurality of eyelets riveted in said sail, and a line looped through each of said eyelets in such a manner as to encircle an individual ring with each loop, said second-mentioned line being 80 secured to said first-mentioned line near the top of the sail.

7 In testimony whereof, I have signed my 85 name to this specification.

8 HANS F. JORGENSEN.
